HIGHWAY SIGNAL FLARE

John K. Lawlor, 19122 Bridwell St., Glendora, Calif.

Filed Oct. 23, 1965, Ser. No. 87,872

Term of patent 7 years

(Cl. D72—1)

FIG. 1.

FIG. 2.

FIG. 3.

FIGURE 1 is an elevational view of a highway signal flare, showing my new design;

FIGURE 2 is a top plan view thereof; and,
FIGURE 3 is a bottom plan view thereof.

I claim:

The ornamental design for a highway signal flare, substantially as shown.
